UNITED STATES PATENT OFFICE.

DANIEL E. POWERS, OF NEW YORK, N. Y., ASSIGNOR, BY MESNE ASSIGNMENTS,
TO THE PATENT PAPER CIGAR BOX COMPANY, OF SAME PLACE.

CIGAR-BOX.

SPECIFICATION forming part of Letters Patent No. 324,589, dated August 18, 1885.

Application filed December 30, 1884. (Model.)

To all whom it may concern:

Be it known that I, DANIEL E. POWERS, a citizen of the United States, residing at New York, in the county of New York and State 5 of New York, have invented certain new and useful Improvements in Cigar-Boxes, of which the following is a specification, reference being had to the accompanying drawings.

This invention relates to a cigar-box composed of paper or straw board, the body thereof consisting of a single piece of straw-board, and the box being of sufficient strength to withstand the usual pressure incident to the packing of cigars.

15 The object of this invention is to provide a box of this character, the corners of which are square, whereby the box has every appearance of an ordinary cedar cigar-box.

In the accompanying drawings, Figure 1 is 20 a plan of the under side of a blank for the body of a box made in accordance with this invention. Fig. 2 is a transverse section of this improved cigar-box. Fig. 3 is an enlarged section of one side of the box and a portion of 25 the bottom thereof, showing the peculiar joint formed between said side and bottom. Fig. 4 is a perspective view of this improved cigar-box.

Similar letters of reference indicate corresponding parts in the different figures.

In the drawings, A represents the blank for the body of the box, and B the lid thereof. The blank A, composed of thick straw-board, or board composed of other suitable paper-stock, is rectangular in shape, and recessed at its sides and ends. This blank comprises a rectangular bottom section, a, rectangular side flaps, b, rectangular end flaps, c c, and re-enforcing square or rectangular semi-end flaps, 40 d d d d, attached to the ends of the rectangular side flaps. The side flaps, b b, are partially severed from the bottom a, to which they remain attached, by means of parallel longitudinal scores z z, which are cut or im- 45 pressed in the blank at points distant from the recessed edges thereof nearly equal to the interior depth of the box to be formed. The rectangular end flaps, c c, are partially severed from the bottom a, to which they remain 50 attached, by the parallel transverse scores y y,

extending between the longitudinal scores z z, and impressed or cut in the blank at points distant from the recessed under edges thereof nearly equal to the depth of the box to be formed plus the thickness of the blank. The 55 re-enforcing semi-end flaps, d d d d, are completely severed from the end flaps, c c, by short longitudinal cuts x x x x, which are continuous with the longitudinal scores z z, and which extend from the ends thereof and in 60 line therewith to the under edges of the blank; and said semi-end flaps are partially severed from the side flaps, b b, to which they remain attached, by short transverse scores w w w w, which extend inward from the side edge of 65 the blank to the cuts x x x x at right angles to said cuts, being the thickness of the blank nearer to the outer edges of the end flaps, c c, than the transverse scores y y. The recesses 70 u u in the side flaps, b b, extend between points opposite the transverse scores y y, said side flaps being thereby provided with square pieces e e e e. The recesses y y, at the ends of the blank, extend between the longitudinal cuts x x, whereby the said end flaps, d d, are 75 made to project endwise beyond the end flaps, c c, a distance about equal to the thickness of the paper-board of which the blank is formed.

In forming the box from the blank thus described, the end flaps, c c, are folded at right 80 angles to the bottom a on the line of the transverse scores y y. The side flaps, b b, are folded at right angles to the bottom a on the lines of the longitudinal scores z z, and the semi-end flaps, d d d d, attached to the side flaps are then folded 85 on the lines of the short transverse scores x x x x over against the end flaps, c c. In the folding of the flaps in the ordinary manner, angular recesses are formed at the corners equal to about half the thickness of the material, which 90 impart an unsightly appearance to the box when completed. This improved box is folded in such manner as to avoid this unsightly appearance, the side flaps, b b, and end flaps, c c, being subjected to pressure or compression 95 from their outer edges during the act of folding, whereby the connecting-web g of the material at the angle between the side flaps and bottom is upset somewhat, so that the severed portions f of the edges of said side and end flaps 100

become flush with the under surface of the bottom *a*, and in folding the semi-end flaps pressure is also put upon them at their inner edges so as to force their partially-severed outer edges 5 out flush with the outer surface of the side flaps, *b*, the increased length of these end flaps enabling them to meet at the center of the box. The projections *e* in the side flaps, *b*, cover the upper portion of the ends of the end flaps, *c*, 10 and secure a flush surface throughout the sides of the box. These semi-end flaps, *d*, together with the end flaps, *c*, constitute the ends of the box, which are of double and uniform thickness throughout. The blank thus folded and 15 upset is properly cemented or pasted at the corners and covered with a layer, *E*, of paper, which hides the joints and assists in strengthening the box. Owing to the recesses in the sides of the blank along the side flaps, said 20 side flaps, when folded, are of less height than the ends of the box, which latter project above the sides a distance equal to the thickness of the cover *B*. The cover is attached at its rear edge by means of a flexible cloth, or other suitable hinge, *F*, to the rear side of the box. A 25 suitable catch or fastening device, *D*, is attached to the front edge of the lid and front side of the box. When the lid is closed, it shuts between the end flaps, and its top surface 30 is flush with the upper edge thereof. As thus constructed the box is strong, cheap, durable, and symmetrical.

I claim as my invention—

1. A rectangular blank for cigar-boxes, recessed at its ends and provided with parallel longitudinal scores along the bottom section, 35 with longitudinal cuts which are continuous with said longitudinal scores and extend from the ends of said scores to the end edges of the blank, with transverse scores which connect the meeting points of said longitudinal cuts and longitudinal scores, and with short transverse scores which extend from said longitudinal cuts to the side edges of the blank, and 40 which are located endwise from the transverse scores a distance equal to the thickness of the blank, substantially as described.

2. A rectangular blank for cigar-boxes, recessed at its sides and provided with parallel longitudinal scores along the bottom section, 50 with longitudinal cuts which are continuous with said longitudinal scores and extend from the ends of said scores to the end edges of the blank, with transverse scores which connect the meeting points of said longitudinal cuts 55 and longitudinal scores, and with short transverse scores which extend from said longitudinal cuts to the side edges of the blank, and which are located endward from said transverse scores a distance equal to the thickness of the 60 blank, the recesses in the sides of the blank extending between points opposite said transverse scores, substantially as described.

3. A box composed of paper-board, the bottom and sides of which are in one piece, the 65 material being partially severed at the angles, the unsevered portions being upset, whereby a square corner is formed, substantially as described.

4. A box composed of paper-board and having double ends, the bottom, sides, and ends being in one piece, the material being partially severed at the angles, the unsevered portion being upset at that point, whereby square corners are formed, substantially as described. 70

5. A box composed of paper-board and provided with double ends extending above the sides and with a cover which shuts between said ends flush with the upper edges thereof, the bottom, sides, and ends being in one piece, 80 the inner layers of the material being integral with the bottom of the box and the outer layers thereof being longer than the inner layers and in sections integral with the sides of the box, the material being partially severed at the 85 angles, the unsevered portions being upset, whereby square corners are formed, substantially as described.

DANIEL E. POWERS.
